Hibbs.*

UNITED STATES PATENT OFFICE

HAROLD D. GRINNELL, OF PITTSFIELD, MASSACHUSETTS, ASSIGNOR TO THE G. C. A. MANUFACTURING COMPANY, OF PITTSFIELD, MASSACHUSETTS, A CORPORATION OF MASSACHUSETTS

CORD COUPLING

Application filed February 3, 1931. Serial No. 513,155.

This invention relates to devices for coupling together the loose ends of cords, ropes and the like, and aims to provide improved means for accomplishing this object.

5 The invention will best be understood from a description of one selected embodiment thereof illustrated in the accompanying drawings, to which reference may be had, and wherein

10 Figures 1, 2 and 3 are top, side and bottom views, respectively, showing the device operatively associated with a rope or cord, the ends of which are secured together; and

15 Fig. 4, an end view of the device, from which the cord has been removed.

The invention comprises two upright rings or bands 10, 11 arranged in parallel and secured to each other in spaced relation by rigid connecting means, such as the bridge members 12, 13, the whole forming a unitary structure. The bridge members are preferably crowned inwardly, effecting four restricted lateral openings 14, two at each end 20 of the device, through which the ends of the cord 15 are passed to form the respective loops 16, 17. The material out of which the bands and bridge members are cut or formed are preferably constructed with straight or 25 unfinished edges about the openings 14, thereby serving more effectively to impinge upon the cord to prevent slipping.

In practice and as an article of manufacture I prefer to construct my device of metal tubing, such as aluminum which is relatively light in weight and may have a proper gauge for strength. The tubing stock may be cut into appropriate lengths, which are then side cut to provide opposite lateral openings. 30 The remaining structure is then shaped with a forming die to impart to the terminal portions or bands an oblong shape and to curve the bridge members inwardly at their mid-dles.

45 The bands 10, 11 are preferably made oblong in cross-sectional outline with uniformly parallel side walls, as shown in Fig. 4, and of a size to conform to the combined dimensions of two courses of the cord, laid side by side without providing any appreciable ex-

tent of clearance, thus avoiding a tendency otherwise of the cords to play and loosen.

In operation, one end of the cord is passed through one of the bands 10, 11, then out through one of the lateral openings 14, then laid over one of the bridge members 12, 13, and doubled back, the remaining free portion of this cord end being inserted into the opposite opening 14 and passed out through the same band, care being used to take up on 60 any slack so that the bight of the cord fits snugly around the enclosed bridge. The same operation is then applied to the opposite end of the cord with respect to the band at the opposite end of the device.

65 While my invention is adapted to secure together opposite ends of the same cord it may also be employed to unite adjacent ends of separate cords to connect them together to form a lengthening line. Again, it should 70 be observed, the use of the device is not restricted to application to cords kept under tension.

75 The invention is not limited to the precise embodiment herein disclosed but is intended to embrace all obvious modifications thereof.

I claim:

1. In combination with a cord or the like, a coupling whose opposite ends are connected 80 respectively with opposite ends of the cord to make a continuous line, said coupling including a pair of rings having their centers in a common axis and arranged in spaced relation, the side walls of each ring being substantially parallel throughout, and a rigid member connecting the rings.

85 2. In combination with a cord or the like, a coupling comprising a pair of upright rings arranged in spaced parallel relation and a longitudinally curved rigid member connecting the rings, each end of the cord forming a loop passing through one of the rings and enclosing the corresponding end of said transverse member.

90 3. As an article of manufacture, a coupling formed of a length of metal tubing having its side walls cut away at opposite points a portion of its length intermediate the extremities, the remaining portions of the side

walls intermediate the extremities being bowed inwardly.

4. In a device of the class described, a unitary structure having parallel tubular end portions spaced apart with their axial centers in alignment and oppositely arranged bars extending between and connecting the end portions, said bars being inclined toward each other to form with the end portions oppositely arranged restricted lateral openings at each end of the device.

5. In a device of the class described, in combination with a cord or the like, a pair of rings arranged in spaced relation and connected together by oppositely arranged curved bridge members formed to provide lateral openings at each end of the device, the opposite ends of the cord forming loops, each loop enclosing a bridge member and passing through a separate ring.

6. A coupling for cords and the like comprising, in combination, a pair of upright rings each enclosing an oblong opening having uniformly parallel side walls, and a curved spacing member connecting and supporting the rings in parallel relation.

In testimony whereof, I have signed my name to this specification.

HAROLD D. GRINNELL.
